ISAAC SNOW, OF LAWRENCE, MASSACHUSETTS, ASSIGNOR, BY MESNE ASSIGNMENTS,
OF ONE-HALF TO HARRY CLOUGH, OF LAWRENCE, MASSACHUSETTS.

FRICITION DEVICE FOR SHUTTLES.

1,099,624.

Specification of Letters Patent.

Patented June 9, 1914.

Application filed January 10, 1913. Serial No. 741,293.

To all whom it may concern:

Be it known that I, ISAAC SNOW, a citizen of the United States, residing at Lawrence, in the county of Essex and State of Massachusetts, have invented certain new and useful Improvements in Friction Devices for Shuttles, of which the following is a specification.

My invention relates to devices in shuttles for the purpose of preventing the filling from running out too freely and from floating. It is used so that the filling may as nearly as possible be kept straight at all times and without kinks. Its purpose is to produce a slight friction or drag on the filling as it is running out through the shuttle eye.

The advantages of my device are its durability and the uniform drag which it exerts on the filling. It also permits lumps and uneven places to pass through without breaking.

My device consists substantially of a disk of rawhide or any other suitable material placed at an angle with the axis of the shuttle and held by suitable means so that the filling must pass under it or along its edge in its course to the shuttle eye, whereby the disk will crawl or move in a rotative manner in a direction transverse to the movement of the filling thus presenting a new surface continually to the filling. The disk which I prefer to use should be suitably confined in a position transverse to or at an angle with the axis of the shuttle and should rest upon a bottom plate in such a manner that the filling must pass between the disk and the plate. With such a disk, there is no regular rotative action, but the disk exerts a drag on the filling which in turn causes the disk to creep, thus presenting a new point of contact continually. The edges of this disk should preferably be rounded and the disk may be made of rawhide, fiber, metal or even glass. As the point of contact of the disk with the filling is constantly changing, the filling cannot cut creases or grooves in the disk.

In the drawings, Figure 1 is a plan view of one form of my device in a shuttle. Fig. 2 is a sectional elevation from the right on the line X—Y of Fig. 1. Fig. 3 is an elevation as from the right side of Fig. 2 of the device before being driven into the shut-

tle. Fig. 4 is a similar view after its legs 5 are driven into place in the shuttle. Fig. 5 is a side elevation of a modification of the holder which is screwed into place instead of being held in place by legs. Fig. 6 is a plan view of the well known suction eye shuttle 60 with the form of my device shown in Fig. 5 in place. Fig. 7 is a side elevation of a leaded or weighted form of disk which I may use. Fig. 8 is a plan view of my device applied to a certain form of threading 65 device in a shuttle. Fig. 9 is an elevation as from the left of the threader shown in Fig. 8 separate from the shuttle. Fig. 10 is a plan view of a well known form of self threading shuttle with my device attached. 70 Fig. 11 is a sectional perspective of the same without the disk and Fig. 12 is a sectional perspective with the disk in place.

In the type of device shown in Figs. 1, 2, 3 and 4, A is the wooden part of the 75 shuttle. B is the metal point thereof. C is the bobbin and D is the filling. H is a disk of rawhide, fiber or any other suitable material and is held in place by a holder such as L. In this form, the holder is stamped 80 out of and bent from a single sheet of metal. It comprises a top plate 51 from which extends a bottom plate 50 in the form of a long curved tongue which terminates at 54. Legs 52 and 53 are bent downward from top plate 85 51 on each side of the bottom plate 50 forming the sides of the device so that the whole holder forms a loose inclosure for disk H. Preferably, near the point where the bottom plate 50 leaves top plate 51 the metal 90 is made somewhat thinner at 59 so that it may be readily bent. This is for the purpose of introducing the disk H into its place without disturbing the curve of bottom plate 50. As shown in Fig. 2, the wood A of the 95 shuttle is recessed to fit holder L.

The legs 52 and 53 serve the purpose of holding the device in place and are driven into holes 56 and 57 in the wood of the shuttle. These holes 56 and 57 preferably extend away from each other as they enter, whereby when the legs 52 and 53 are driven in, the holder L is firmly held in place. Disk H is thus held loosely between legs 52 and 53, top plate 51 and bottom plate 100 50. The holder L may be so placed that disk H will form an acute angle or a right angle with the filling D as it passes from

the bobbin out through the shuttle eye. It should also be so placed that the filling D will slip down along tongue 50 underneath disk H so that it will normally run along the edges of legs 52 and 53 under the disk as shown in Fig. 2. It will be readily seen that in this manner, the disk H exerts a friction on the filling and while it will be lifted and moved so as to make it crawl more or less, it will never be out of contact with the filling long enough to permit the filling to float. It will thus cause a substantially fixed drag on the filling.

As shown in Fig. 7, I may use a disk 15 such as M loaded with lead or other heavy material as 60 in order to increase the friction.

In Fig. 5 is shown a modification of my device which has a back plate 81, a bottom 20 plate 80 and instead of legs, the side supports 82 and 83 all suitably bent from one sheet of metal. A pin 85 passes through and is fixed in sides 82 and 83 and passes loosely through a large hole 86 in rawhide 25 disk 87 thus holding it loosely in place. A screw 88 which passes through back plate 81 into the wood P of the shuttle holds the device in place.

In Figs. 8 and 9, I show the device in connection with a shuttle-threader or self threading shuttle of a design upon which I have applied for Letters Patent as threading device for shuttles, January 10, 1913, Serial No. 741,294. The threader F is preferably formed of a single sheet of metal and is inserted into a threader recess 21 adjoining the bobbin recess 20 in the wood N of the shuttle so shaped as to receive it. 22 is the groove in the wood through which the filling passes into the shuttle eye 23. The threader F at the bottom 30 is of semi-cylindrical form while the side walls 31 and 32 continue straight upward for a certain distance. An ear 33 is bent on one side 45 and another ear 34 on the other side to rest in recesses 60 and 61 cut into the wood N on each side of the threader recess 21. Screws 65 and 63 pass through suitable holes in each ear 33 and 34 into the wood N of the 50 shuttle and hold threader F in place. The top edge 35 of side 31 is so formed as to just pass inside the depending tip 37 of a top guide plate 36 as shown in Fig. 9. The edge of top guide plate 36 nearest bobbin C 55 has a long slope as shown in Fig. 8 while the far edge slopes slightly backward in line with a vertical slot 24 in side 32. The slot 24 in the side 32 which when the parts are in place adjoins slot 25 in the wood of the 60 shuttle connects with an eye in side 32 not shown which adjoins the shuttle eye 23 when the parts are in place. It will be seen that this device is a self-threading shuttle as by bringing filling D forward, it slips 65 under nose 37 thence by bringing it back-

ward it slips to the right along the front of plate 36 through slots 24 and 25 and lands in the eye of the threader which coincides with the eye 23 of the shuttle. Through the side wall 32 of threader F, I insert retaining side plates 40 and 41 for disk H which extend part way across threader F and are cutaway at the bottom as shown at 42 in Fig. 9 so that they form grooved bearings for the filling D. The top guide plate 36 75 extends over the top of plates 40 and 41 sufficiently to hold therein the disk of rawhide H which extends across the shuttle with its axis coinciding with the longitudinal axis thereof. Disk H is loosely held between bottom 30, sides 31 and 32, side plates 40 and 41 and top guide plate 36.

In Figs. 10, 11, 12, I show the device attached to a well known form of self threading shuttle. The wood of the shuttle is 85 shown at T and the metallic threader at M. In a recess 90 behind the threader M, I insert a holder which comprises a top plate 91, a bottom plate 92, a side plate 93 and a pin 94 which is driven into threader M passing loosely through a large hole in the disk 97 as shown.

In Fig. 6, the holder shown in Fig. 5 is shown in place in the well known suction shuttle. P represents the wood of the shuttle and R the shuttle eye while the holder is screwed in place to the side wall 89 as shown in Fig. 5.

The essence of my invention is the arrangement of a holder or inclosure through 100 which the filling must pass into the shuttle eye with a confined mobile curved body such as a cylinder or disk made of suitable material with its axis substantially parallel with the course of the filling or the axis of the 105 shuttle and so confined that it has some freedom of action but will continually return by the force of gravity to a position wherein it rests upon the filling and will continually or intermittently keep it in contact 110 with the bottom of the holder. Instead of being confined in an inclosure or holder, I may use a disk bored with a relatively large hole and kept in place by means of a pin 115 which passes through such hole.

What I claim as my invention and desire to cover by Letters Patent, is:

1. In a tension device for shuttles, a disk located with its axis substantially parallel with the course of the filling and so confined as to be movable vertically but not longitudinally and rotative in a direction transverse to the movement of the filling and normally in contact with the filling at its edge.

2. In a tension device for shuttles, an inclosure comprising a top plate, a bottom plate, and sides, said sides being transverse to the axis of the shuttle, combined with a movable disk located in such inclosure 130

transversely of the shuttle and normally resting on the bottom plate and confined in movement by said inclosure.

3. In a tension device for shuttles, the combination of a shuttle having a suitable recess, with a holder bent from one piece of sheet metal and comprising a top plate, a bottom plate so curved as to fit the bottom of the recess and legs which form the sides and are bent from the top plate said legs being driven into suitable holes in the shuttle, together with a disk loosely inclosed between the top plate, the bottom plate and the legs as described.
- 15 4. In a tension device for shuttles, the combination of a shuttle having a suitable recess, with a holder bent from one piece of sheet metal and comprising a top plate, a bottom plate so curved as to fit the bottom of the recess and legs which form the sides and are bent from the top plate said legs being driven into suitable holes in the shuttle, together with a loaded disk loosely inclosed between the top plate, the bottom plate and the legs as described.

- 25 5. In a tension device for shuttles, the combination of a shuttle having a suitable recess, with a holder bent from one piece of sheet metal and comprising a top plate, a bottom plate so curved as to fit the bottom of the recess and having a thin portion in proximity to the top plate, and legs which form the sides and are bent from the top plate said legs being driven into suitable

diverging holes in the shuttle, together with 35 a disk loosely inclosed between the top plate and the bottom plate and the legs as described.

6. In a tension device for shuttles, a holder formed of a single piece of sheet 40 metal comprising a top plate, a curved bottom plate and legs bent down on each side of the bottom plate, together with a disk loosely inclosed between the top plate, the bottom plate and the legs. 45

7. In a tension device for shuttles, a bottom plate, combined with a disk located with its axis substantially parallel with the axis of the shuttle and which is confined in movement and is so placed that the filling 50 must pass between it and the bottom plate, said disk being capable of a limited vertical movement and having its edge normally resting on the filling.

8. In a tension device for shuttles, an inclosure comprising a bottom plate and sides transverse to the axis of the shuttle, combined with a disk located in such inclosure transversely of the shuttle and normally resting on the bottom plate and confined in 60 its movement by said inclosure.

In testimony whereof I hereto affix my signature in presence of two witnesses.

ISAAC SNOW.
